UNITED STATES PATENT OFFICE.

JOHN VAN DEVELDE, OF CLEVELAND, OHIO, ASSIGNOR OF ONE-HALF TO
HERBERT H. HYMAN, OF SAME PLACE.

PAPER BARREL.

SPECIFICATION forming part of Letters Patent No. 614,218, dated November 15, 1898.

Application filed July 5, 1898. Serial No. 685,099. (No model.)

To all whom it may concern:

Be it known that I, JOHN VAN DEVELDE, a citizen of the United States of America, and a resident of Cleveland, Cuyahoga county, 5 and State of Ohio, have invented certain new and useful Improvements in Paper Barrels, of which the following is a specification.

This invention relates to paper barrels; and it consists in the new construction and combinations, substantially as hereinafter described, and pointed out in the claim.

In the accompanying drawings, Figure 1 is an external view, in side elevation, of my new paper barrel. Fig. 3 is a vertical section of 5 the same. Fig. 2 is an end view of the barrel. Figs. 4, 5, and 6 are sectional views of one end of a barrel, showing different methods of attaching the heads. Fig. 7 is a side and an edge view of a hoop. Fig. 8 is a side 50 and an edge view of the head-fasteners.

A represents the body of the barrel, which is made of paper by rolling the paper on suitable rollers or mandrels designed for the purpose, having a little greater diameter at their 5 middle part for making the bilge at the middle of the body. As the paper is rolled on said rollers glue or other suitable adhesive material is applied for the sticking of the layers of paper together. At the same time 55 the paper is rolled wires b b are also rolled in between the layers of paper, the purpose of which is to give additional strength to the cylinder. The mandrel on which the paper is rolled has tapering grooves a a, formed in the 60 surface from the ends toward the middle, and the impression-roller which works in conjunction with the mandrel has corresponding tapering ribs, which act to impress the paper into the said grooves for the purpose of making tapering crimps in the cylinders and thereby reducing the diameter of the cylinder gradually from the middle for producing the bilge. The hoops D consist of flat bars of iron of the usual kind, but are provided with 65 barbs d, punched in them at suitable intervals, and have in one end a hole C and in the other end a sharp barb B. These hoops are applied to the cylinders after they have been 70 formed as above described by placing the ends of the hoops having the holes upon the 75 cylinder with the barbs inward toward the paper, and by the rotation of the cylinder the hoops are rolled onto the cylinder, the barbs are inserted into the paper, the end barb B entering the hole C, when the revolution is 80 completed, and said barb is also forced into the paper and clenched on the inside. The body of the barrel is now completed and ready for the placing in and securing of the heads, which is done in the following manner: The 85 heads E are also made of paper, same as the cylinders, of suitable thickness, and are formed with corrugated flanges e to fit into the crimped or corrugated ends of the cylinders, as seen in Fig. 2. The means for securing the heads in place consist of wires or 90 flat strips of metal F, having sharpened ends or points f, as shown in Fig. 8. One method of applying these fasteners is shown in Fig. 4, which consists in forcing the points of the 95 wires or strips into the cylinder, as seen at i, then turning said wires or strips over the chime or ends of the cylinder and flanges of the heads. Another method is to insert the points of the wires or strips into the paper on the inside of the cylinder, as seen at j, Fig. 5, the wires or strips having knobs or bent projections k to form stops for the heads to rest against when in place. The heads are then forced down into place, which force drives the sharp points of the fasteners into the paper. Then, when down, the projecting ends of the wires or strips are bent inward and down over the edge of the flanges of the heads. Another and preferable method is, first, to place the 100 fastening wires or strips on the mandrel in proper places, with points outward, at the beginning of the rolling on of the paper, and as the mandrel revolves the paper is punctured by the points. There are provided annular 105 grooves in the impression-roller for the points to enter as the same revolves. This is done during the first revolution. Then as the second revolution begins the wires b, before mentioned, are started to be rolled in.

Having described my invention, what I claim, and desire to secure by Letters Patent, is—

A paper barrel consisting of a cylindrical body A, having tapering crimps or corrugations *a a* from near the middle to the ends, wires *b b* between and outside of the layers 5 of paper composing the body, heads E E having crimped or corrugated flanges *e*, fitted to the crimped or corrugated ends of said body, head-fasteners F F, and the barbed hoops D

D, constructed and combined substantially as described.

Signed by me at Cleveland, Ohio, this 1st day of July, 1898.

JOHN VAN DEVELDE.
